Martin Grünstein, Elgersburg, Germany, assignor
to the firm Müller & Grünstein, Elgersburger
Feuerzeugfabrik, Elgersburg, Germany

Application May 5, 1933, Serial No. 48,018
In Germany February 8, 1933

Term of patent 3½ years

To all whom it may concern:

Be it known, that I, Martin Grünstein, a citizen of Germany, residing at Elgersburg, Thuringia, Germany, have invented a new, original, and ornamental Design for a Pocket Lighter, of which the following is a specification, reference being had to the accompanying drawing, forming a part thereof.

Fig. 1 is a front elevational view;

Fig. 2 is a side elevational view; and
Fig. 3 is a rear elevational view of a pocket lighter showing my new design.

I claim:

The ornamental design for a pocket lighter, as shown.
In testimony whereof I have signed my name to this specification.

MARTIN GRÜNSTEIN.
